(57) CLAIM

The ornamental design for a chair with underseat storage, as shown and described.

DESCRIPTION

FIG. 1 is a top right perspective view of the chair with underseat storage of the present invention;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a top left perspective view thereof; and,

FIG. 8 is a top right perspective view, illustrated with the seat in a lifted position.

The portions of the chair with underseat storage illustrated in broken lines form no part of the claimed subject matter.
